UNITED STATES PATENT OFFICE.

HENRY BLY, OF RUTHTON, MINNESOTA.

CLOTHES-DRYING APPARATUS.

1,411,265.

Specification of Letters Patent. Patented Apr. 4, 1922.

Application filed June 7, 1921. Serial No. 475,591.

To all whom it may concern:

Be it known that I, HENRY BLY, a citizen of the United States, residing at Ruthton, in the county of Pipestone and State of Minnesota, have invented new and useful Improvements in Clothes-Drying Apparatus, of which the following is a specification.

The object of my present invention is the provision of a clothes drying apparatus characterized by simplicity and inexpensiveness in construction and by the facility with which clothes may be placed on the lines, and the lines may be afterward rendered taut so as to adequately support the clothes.

To the attainment of the foregoing, the invention consists in the improvement as hereinafter described and definitely claimed.

In the accompanying drawings, forming part of this specification:—

Figure 1 is a side elevation illustrative of my novel apparatus.

Figure 2 is a top plan view of the same.

Figure 3 is an end elevation of the apparatus.

Similar numerals of reference designate corresponding parts in all of the views of the drawings.

Among other elements my novel apparatus comprises two arched supports 1 and 2 of gas pipe or other appropriate material, the legs of which are adapted to be embedded in the ground and fastened by cement or other appropriate means. The said supports 1 and 2 are arranged in spaced and parallel relation, and the support 2 is provided between the lower portions of its legs or uprights with a cross rod 3 as best shown in Figure 3. On the upper bar of the said support 2 are brackets 4 in which are carried sheaves 5.

This, however, is not of the essence of my invention, and it will therefore be understood that it is fully within the purview of my invention to attach the sheaves 5 to the upper cross bar of the support 2 in any manner compatible with the purpose of the invention.

In addition to the supports 1 and 2 the apparatus comprises a plurality of clothes lines or cables 6. The said cables 6 are connected at one end to the cross bar 7 of the support 1 and are then carried to and over the sheaves 5 and downwardly from the said sheaves 5 as clearly shown in Figures 1 and 3. On the lower ends of the lines or cables 6 are weights 8, and carried by and depending from the said weights 8 are coiled re-

tractile springs 9, equipped at their lower ends with hooks 10, designed to be engaged after the manner shown in Figure 3 with hooks or eyes 11 on the cross bar 3 of the support 2.

In the practical use of my novel apparatus, the clothes are hung and appropriately fastened on the portions of the cables or clothes lines 6 between the two supports 1 and 2 while the springs 9 are detached from the hooks or eyes 11. At this time the portions of the lines or cables 6 between the supports 1 and 2 can be sagged or drawn downwardly against the action of the weights 8 in a very convenient manner, and then after each line is supplied with clothes the spring 9 of that line is engaged with its complementary hook or eye 11 when the line will be rendered taut and the clothes thereon between the supports 1 and 2 will be adequately supported.

When it is desired to remove clothes from the lines or cables 6 the operation described is reversed—i. e., the hook or spring of the particular line is detached from its complementary hook or eye 11 so as to render the line slack and permit of it being drawn downwardly between the supports 1 and 2 for the convenient unfastening and removal of the clothes at which time the weight on the line alone will be sufficient to prevent the clothes thereon from reaching to and dragging on the ground.

Notwithstanding the simplicity and inexpensiveness of my novel apparatus it will be readily observed that the apparatus is susceptible of being very conveniently and quickly operated both as regards the putting out of clothes to dry and the taking in of the clothes.

In the preferred embodiment of my invention the weights 8 and the springs 9 as well as the other metallic portions of the apparatus will be galvanized so as to better withstand exposure to the weather.

I have entered into a detailed description of the construction and relative arrangement of parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made

such as fall within the scope of my invention as defined in my appended claims.

Having described my invention, what I claim and desire to secure by Letters-Patent, is:—

1. A clothes drying apparatus comprising spaced arched supports arranged in substantial parallelism, one of the said supports being provided with a lower cross bar and fastening members thereon, sheaves carried by the upper cross bar of said support, cables connected at one end to the cross bar of the other support and carried over and downwardly from the sheaves, weights on the downwardly extending portions of the cables, and retractile coiled springs carried by and pendent from the weights and having means at their lower ends to detachably connect them to the fastening members on the said lower cross bar.

2. A clothes drying apparatus comprising spaced and substantially parallel arched supports, guides on the cross bar of one support, cables connected at one end to the cross bar of the other support and passed through the said guides and downwardly therefrom, weights on the pendent portions of the cables, and springs connected to and depending from the weights and adapted to be detachably connected at their lower ends to the lower portion of the adjacent support. 25

3. The combination of spaced supports, a guide on one support, a cable connected to one support and passed through the guide, a weight on said cable, and a coiled retractile spring on the weight and adapted to be fastened to an adjacent support at its end remote from the weight. 35

In testimony whereof, I affix my signature.
HENRY BLY.
